UNITED STATES PATENT OFFICE.

ISAAC A. REYNOLDS, OF PITTSBORO, INDIANA.

FENCEPOST.

1,334,053.

Specification of Letters Patent. Patented Mar. 16, 1920.

Application filed August 23, 1919. Serial No. 319,421.

To all whom it may concern:

Be it known that I, ISAAC A. REYNOLDS, a citizen of the United States, and a resident of Pittsboro, county of Hendricks, and State of Indiana, have invented a certain new and useful Fencepost; and I do hereby declare that the following is a full, clear, and exact description thereof, reference being had to the accompanying drawings, in which like numerals refer to like parts.

This invention relates to a fence post and particularly to that type of post adaptable for corners and gates, whereby the post will be firmly anchored to withstand the strain exerted by the tension of the fence.

The main object of this invention is to provide an anchorage for the post which will be entirely hidden and concealed beneath the ground, but at the same time anchor the post from the top. This is accomplished by providing a web base having anchoring rods extending from the ends thereof into the post beneath the surface of the ground, said anchoring rods being secured at their inner ends to the top of the post inside thereof.

By means of this construction, not only a post of neat appearance is provided, but a very staple and strongly braced post, which will be firmly anchored in the ground by means invisible above the ground surface.

The full nature of this invention will be fully understood from the accompanying drawings and the following description and claims.

In the drawings Figure 1 is a side elevation of the post. Fig. 2 is a central vertical cross section through the post and anchor. Fig. 3 is a section taken on the line 3—3 of Fig. 2.

In the drawings there is shown a hollow cylindrical metal fence post 10, which is mounted on a web anchoring base 11 having with a plurality of radially extending arms 12 provided with slits or holes in their extreme ends in which are engaged anchoring rods 13 by means of the nuts 14 screwed on the end thereof. The radial arms are provided with fins 15 extending longitudinally thereof and a central projection 16 over which the bottom of the hollow post is adapted to fit for holding it in place. The post 10 is provided with a plurality of longitudinal slots 17, each slot corresponding to an arm 11 and placed in said post at a point wherein

they will be below the surface of the ground when the post is set. The rods 12 are adapted to extend through said slots into said posts so as to have their heads 18 engaged by the anchoring disk 19 which is provided with radial slots corresponding to the longitudinal slots 17. The disk 19 is secured to a cap 20 mounted on top of the post, by the central rod 21, which is adapted to cause the disk 19 to pull the anchoring rods taut when the nut 22 is tightly screwed on the rod 21.

By means of this construction, when the anchoring base is firmly set in the ground, it will anchor the post through the medium of the anchoring rods, firmly upon the top thereof, and at the same time the anchoring and bracing of the post will be entirely invisible above the surface of the ground. It will also be observed that such post may be very cheaply constructed from gas pipe or boiler tubing mounted on a cast iron base and assembled with a plurality of tie rods. However, in place of tie rods, cables could be used as well, and, therefore, it is contemplated that this invention and the claims therefor be restricted to the use of rods and where the term rod is used, the term cable may be substituted therefor without departing from the invention set forth.

The invention claimed is:

1. A fence post comprising in combination a tubular upright member, an anchoring base upon which said member is mounted, said base having a plurality of openings upon its outer edge, said upright member being provided with a similar number of longitudinal slots between the ends thereof, a slot and an opening lying in substantially the same vertical plane, a similar number of tie rods engageable in said openings and extending upwardly and inwardly through the associated slots, a cap mounted upon the upper end of said tubular member to close the same, a rod suspended centrally from said cap and extending downwardly within said member, a disk supported by said rod and slidable within said tubular member adjacent said longitudinal slots, said disk having a similar number of slots, each of said slots being positioned adjacent a longitudinal slot and in substantially the same plane thereof, said slots being adapted to seat said tie rods which extends through said longitudinal slots and into said tubu-

lar member, and means associated with said disk supporting rod for drawing said disk upwardly to tauten said tie rods to brace said tubular member and secure the tie rods, 5 disk, supporting rod and the tubular member in adjusted position.

2. A fence post comprising in combination a tubular upright member closed at its upper end, an anchoring base upon which 10 said member is mounted, said base having a plurality of openings upon its outer edge, said upright member between the ends thereof being provided with a similar number of longitudinal slots, each slot being positioned in a vertical plane including one of 15 said openings, a similar number of tie rods having one end engageable in said openings and extending upwardly through the cor-

responding slot into said tubular member, a disk positioned transversely of said tubular member and longitudinally slidable therein, 20 said disk being provided with a similar number of openings, each opening lying substantially in one of said vertical planes, said openings being adapted to coöperate with 25 the upper ends of said tie rods to seat the same, and adjustable means connecting said disk and the upper end of said tubular upright for drawing the disk upwardly to tauten said tie rods and brace said tubular member, 30 said means securing said disk in the tautened position.

In witness whereof I have hereunto affixed my signature.

ISAAC A. REYNOLDS.
